[57] **CLAIM**

The ornamental design for a valved closure for a container, as shown and described.

DESCRIPTION

FIG. 1 is a top perspective view of a valved closure for a container showing my new design, illustrated with the valve open;

FIG. 2 is a top plan view thereof, illustrated with the valve closed;

FIG. 3 is an end view thereof from line 3—3 of FIG. 2;

FIG. 4 is a side elevation view thereof from line 4—4 of FIG. 2;

FIG. 5 is an end elevation view from line 5—5 of FIG. 2; and

FIG. 6 is a bottom plan view thereof.

The broken lines in FIGS. 1 and 4 are for illustrative purpose only.
